CLAIM

The ornamental design for a bite guard, as shown and described.

DESCRIPTION

FIG. 1 is a front, right, perspective view of a bite guard showing my new design;

FIG. 2 is a front view thereof;

FIG. 3 is a rear view thereof;

FIG. 4 is a bottom view thereof;

FIG. 5 is a top view thereof;

FIG. 6 is a right side view thereof; and,

FIG. 7 is a left side view thereof.

The portions of the figures illustrated in broken lines depict portions of the bite guard that are not part of the claimed subject matter.
